UNITED STATES PATENT OFFICE.

RICHARD FELDTKELLER, OF CHARLOTTENBURG, GERMANY. ASSIGNOR TO SIEMENS & HALSKE AKTIENGESELLSCHAFT, OF SIEMENSSTADT, BERLIN, GERMANY, A COMPANY OF GERMANY.

ARTIFICIAL LINE.

Application filed March 31, 1926, Serial No. 98,642, and in Germany December 9, 1924.

This invention relates to artificial lines for balancing loaded telephone lines and is an improvement in the artificial line described and claimed in the Patent No. 5 1,647,985 granted to Walter Deutschmann, on November 8, 1927.

The application referred to above describes a simulation of the impedance of loaded lines by means of a symmetrical network corresponding to one link of the line, the network having the same iterative impedance as the line, the cut-off frequency, however, being higher than that of the line and the network being closed by an ohmic 10 resistance.

The present invention includes a further development of this simulation. According to the invention the network has an unsymmetrical construction, by means of which 20 the imaginary part of the iterative impedance of the cable is better simulated for the higher speech frequencies. The simulation of this imaginary part is also improved for low frequencies according to the invention, by means of a condenser connected to the line in front of the simulating network. The arrangement of the invention can be applied both for simulating a cable by itself and for simulating cables which are 25 closed by a ring-translator and ringing current blocking condensers as usual when in operation. In the same way one can simulate cables which are extended by distorting artificial lines, the characteristic constants 30 of which depend on the frequency in almost the same manner as those of the cable.

The underlying principle of the invention is explained by the embodiment of the invention illustrated in Fig. 1 and the 40 graphs of Figs. 2 and 3. In Fig. 1 the network consists of the coil L , the ohmic resistance r and the condensers C_1 and C_2 which are of different size according to the invention. The terminal of the network is 45 closed by the ohmic resistance R , of the magnitude

$$\sqrt{\frac{L_k}{C_k}}$$

50 in which L_k and C_k signify the induction and capacity of the cable. The quantity expressed by the above formula is the value of the characteristic impedance of the line at low frequencies and is known as the nominal 55 characteristic impedance. The condenser C_0

is connected to the line in front of the network. Fig. 2 illustrates the real and imaginary part of the iterative impedances of the cable and various simulations as a function of the frequency. The curves 1 represent the cable, curves 2 a simulation in which C_1 and C_2 are equal and C_0 is absent, curves 3 an unsymmetrical simulation with different values of C_1 and C_2 but without C_0 , and the curves 4, the simulation illustrated in 60 Fig. 1.

As is evident from the curves representing the imaginary part, the curve 1 of the cable originates from large negative values and bends close to the zero line, remaining 65 constantly below the latter, however, whereas the curve 2 for the symmetrical simulation is entirely in the positive range. Curve 70 3, for an unsymmetrical connection, shows negative values for higher frequencies, and by connecting the condenser C_0 the simulation 75 will have a negative reactance, which can also easily be adjusted to that of the cable in the low frequency range as seen 80 from curve 4.

The variations of the magnitude of the imaginary part for higher frequencies in general present no disadvantage in practice, but on the contrary, a great advantage. When in operation the cable is terminated 85 by a ring-translator and ringing current blocking condensers. The initial resistance is thereby changed in such a manner that its imaginary components assure high negative values for the entire speech frequency 90 range, whereas the real part is changed very slightly. According to the invention the unbalance of the network and the longitudinal condenser C_0 can be selected in such a manner 95 that a simulation is obtained without making it necessary to simulate the ring-translator and the ringing current blocking condensers in the same way. The curves representing this case are plotted in Fig. 3. The numerals of the separate curves 100 have the same significance as in Fig. 2. Fig. 3 shows that an excellent simulation can be constructed in this case.

When the repeater sections are too short, it is desirable to connect an artificial extension to the cable, which reduces its attenuation to the value of the normal repeater section without noticeably changing the initial resistance. It is most suitable to connect it between the ring-translator and re- 105

peater, and it will influence the real part only in the higher frequencies. Also in this case the simulations constructed according to the invention can be applied without making it necessary to simulate the ring-translator, the blocking condensers and the extension line by simular elements.

What is claimed is:

1. An impedance network for simulating the impedance of the long coil-loaded line, comprising an unsymmetrical II type network corresponding in form to one section of the line to be simulated, and having approximately the same nominal characteristic impedance, but being proportioned in ac-

cordance with a higher cut-off frequency than that of the line, and an ohmic resistance connected to two terminals of said network, said ohmic resistance having a value substantially equal to the nominal characteristic impedance of the line. 20

2. A balancing network in accordance with claim 1, and a condenser in series therewith whereby the combination is adapted to simulate more closely the impedance of the line 25 at low frequencies.

In witness whereof, I hereunto subscribe my name this 1st day of March A. D., 1926.

RICHARD FELDTKELLER.
